RALPH E. SMITH, JOHN C. GAY, AND ROY J. ARNOLD, OF GALION, OHIO, ASSIGNEES
TO THE GALION METALLIC VAULT COMPANY, OF GALION, OHIO, A CORPORATION
OF OHIO.

AUTOMATIC DUMP BODY.

Application filed February 16, 1925. Serial No. 9,580.

To all whom it may concern:

Be it known that we, RALPH E. SMITH, JOHN C. GAY, and ROY J. ARNOLD, citizens of the United States, residing at Galion, in the county of Crawford and State of Ohio, have invented certain new and useful Improvements in Automatic Dump Bodies, of which the following is a specification, reference being had therein to the accompanying

10 drawing.

Our invention relates to dump bodies and in particular to an automatic type of dump body, generally known as a hopper type.

The object of our invention is to provide an automatic body of the hopper type which is particularly adaptable for use in carrying and dumping concrete and other wet mixtures. It is necessary in dumping such material to secure a much greater 20 dumping angle than is necessary with other types of materials and other types of bodies.

It is a further object of our invention to provide a body and supports therefor so arranged that when the body is released at one 25 end the weight of the material in it will unbalance the body and cause it to turn upon its successive supports until the body is completely discharged whereupon the material having left the body, the body can be 30 turned on its pivotal supports to its original position to be reloaded.

It is a further object to provide a simple form of pivotal support which shall permit of this complete dumping action, which 35 shall be easy to construct and cheap to manufacture, which shall be subjected to the minimum wear, and which will not become clogged with foreign material preventing its operation.

40 Referring to the drawings:

Figure 1 is a side elevation partially in section of the dump body, its supporting pivots and frame. This view also shows the relative position of the body to the cab seat, 45 cab, and the method of unlocking the body;

Figure 2 is a section on the line 2—2 of Figure 1;

Figure 3 is a section on the line 3—3 of Figure 1;

Figure 4 is a detail elevation showing the 50 chain and spring control for limiting the dumping movement of the body to prevent it from rocking off of the frame completely on dumping; and

Figure 5 is an elevation in detail of the 55 rocking casting and hook.

Referring to the drawings in detail, 1 is a body frame U-shaped in section. Such a frame member is located on either side of the truck or vehicle on which this mechanism is mounted. These spaced parallel side members 1 are connected together by bolts 2 to an angle iron 3 which extends beneath and across the end of the member 1. This angle iron 3 carries an angle bracket 4 60 which is provided with an eye 5 carrying a pivot rod 6 held in position in the bracket by the cotter pin 7. This rod 6 carries a bracket 8 in which is threaded the latch bolt 9. This bolt is held in position by the nut 70 10. The upper end of the bolt is provided with a hook 11. This hook 11 engages with a cross rod 12 carried beneath and spaced from the bottom of the body or hopper 13 on an angle bracket 14 which is connected 75 at one end as at 15 to a bolt 16 to the vertical wall 17 on the front of the dump body and to an upturned flange 18 on the bottom wall of the dump body. This bottom wall extends along the bottom and thence upwardly at an angle of approximately 45 degrees to form the rear wall 19 of the dump body. 71 is a return spring for the latch.

This bracket 14 extends beneath the bottom of the dump body and then downwardly 85 into a flange 20 which is connected by a bolt 21 to a transverse angle iron support 22 which is adjacent to the bottom of the dump body and serves to position the dump body at its front end above the side rails when in 90 a predetermined position. When the transverse angle iron 22 is in such a position that its lower edge 23 rests upon the top of the side rails 1 then the latch bolt 9 can be

hooked over the rod 12 carried by the bracket 14. This holds the body in its horizontal position for loading or carrying a load or for traveling empty. This latch bolt 9 is controlled by a link 24 pivoted on the bolt at 25 on a cross pin 26. This link 24 proceeds forwardly to a point where it passes through an angle bracket 27 in which it is adjustably held and positioned by a nut 28 working on the threaded end 29 of the link 24. This bracket 27 is connected to an actuating lever 30 which extends adjacent to the cab seat 31, where the operator is located. A lever 30 is pivoted on the cab 10 floor 32 on an upstanding angle bracket 33, which is attached to the floor board 32 by the bolt 34. The back of the cab is designated 35.

The upper edges of the body are turned 20 over as at 36.

The side rails 1 are joined together by a plurality of spaced rods or bars 37, 38 and 39. These bars occur in the order they are named reading from the front of the vehicle to the rear. The bars 37 and 38 are spaced at the same elevation but the bar 39 is located in a substantially lower plane than are the first two bars and at a greater distance from the nearest bar 38 than the bars 30 37 and 38 are from each other. As will be hereinafter explained, this provides for a lowering of the pivot point about which the body is turning when dumping which facilitates the dumping of material without accumulation or sticking in the hopper. These rods are maintained in position by the cotter pins 40. They are supported in the side rails in collars 41 which are longer than the side rails are thick so that a broad bearing 40 surface is provided for these rods which prevents wear.

The forward rod 37 is also provided with a bolt 42 having an eye 43 in which is hooked a helical spring 44. The other end 45 of the spring is connected to a link 45. This link has connected thereto a short chain 46 which is connected to the inside rear face of the angle iron 3 by a hook or eye 47. This chain serves to suspend in a predetermined 50 position the lower end of the spring 44.

The link 45 has also connected to it a longer chain 48 which passes forwardly beneath the transverse angle iron 3 and upwardly to a bracket at the forward end of 55 the body designated 49. This chain limits, and through the spring yieldingly cushions the rearward movement of the body when it is being dumped.

In order to permit this dumping the body 60 is provided on either side with spaced inwardly facing angle irons having transverse members 50 and vertical members 51. The transverse members lie along the bottom of the body adjacent the side rails 1. These 65 depending ribs 51 carry bolts 52 which at-

tach thereto the brackets or jaws which serve as the supports for the body as these jaws rock upon the rods 37, 38 and 39 successively. Two brackets are provided on either side. The first or forward bracket consists of a single member having an overlapping flange 53 which travels rearwardly and upwardly at 54 parallel to the flange 51 which travels rearwardly and upwardly substantially from one end of the body to the other beneath the body. This first or forward bracket has two downwardly extending, widely flaring jaws 55 and 56 which rest respectively upon the rods 37 and 38. A hook member extends between the rods 37 and 38 over this side bracket as at 57 and thence forwardly beneath the rod 38 as at 58, to limit the upward movement of the body when it is in its horizontal position ready to be filled, or filled.

Carried on the rear wall portion of the body are the brackets 59 on either side of the body attached to the flange 51. These brackets carry the jaws 60 which rock upon the transverse rod 39. Each jaw is provided with a forward vertical brace 61.

Across the body is provided a brace 62 on the wall 19 on the outside thereof.

It will be observed in Figure 2 that the side wall 63 of the body terminates in a flange 64 extending beneath the bottom of the body.

It will also be noted that the jaws 56 and 55 are broadened as at 65 to provide broad bearing surfaces and are provided with flying buttresses 66 and 67 to add strength to the structure.

The side rails 1 are attached by the bolts 68 to the truck 69. The method of attachment will vary depending upon the type of body and the like.

The forward end of the bracket 53 is provided with an outwardly extending shoulder which serves as a further body support on the side rails. This shoulder is marked 70.

It will be understood that we desire to comprehend within our invention such modifications as may be necessary to adapt it to varying conditions of use. We do not desire to confine ourselves to details of construction and the like.

Having thus fully described our invention, what we claim as new and desire to secure by Letters Patent, is:

1. In an automatic dump body construction, a supporting frame having spaced side members and transverse supports joining said spaced side members, a dump body having an overhanging rear portion and so arranged that when empty it will maintain the position to be loaded and loaded will tend to attain a position to unload, a plurality of spaced jaws arranged on either side of said body on the bottom and rear wall thereof, said jaws being adapted to suc-

cessively rock upon the transverse supports one of said jaws being located at the body bottom near the rear wall of the body, another at the corner of the body bottom and 5 the rear wall of the body, and the third on the rear wall of the body, and means adjacent the front of the bottom of the body for supporting the body in horizontal position when it is resting on the forwardmost trans- 10 verse support and forwardmost jaws, the rearmost of said transverse supports being lower than the forward supports, and a depending bracket on each side of the body extending between two of said supports and 15 under one of them.

2. In an automatic dump body construction, a supporting frame having spaced side members and transverse supports joining said spaced side members, a dump body hav- 20 ing an overhanging rear portion and so arranged that when empty it will maintain the position to be loaded and loaded will tend to attain a position to be unloaded, a plurality of spaced jaws arranged on either 25 side of said body on the bottom and rear wall thereof, said jaws being adapted to successively rock upon the transverse supports, one of said jaws being located at the rear of the body bottom, another at the corner 30 of the body bottom and the rear wall of the body and the third on the rear wall of the body, and means adjacent the front of the bottom of the body for supporting the body in horizontal position when it is resting on 35 the forwardmost transverse support and forwardmost jaws, the rearmost of said trans- 40 verse supports being lower than the forward supports, and a depending bracket on either side of the body extending between two of 45 said transverse supports and under one of them, and limiting means having associated therewith resilient means to limit the rearward movement of said body to prevent it leaving the supports entirely.

45 3. In an automatic dump body construction, a supporting frame having spaced side members and transverse supports joining said spaced side members, a dump body hav- 50 ing an overhanging rear portion and so arranged that when empty it will maintain the position to be loaded and loaded will tend to attain a position to be unloaded, a plurality of spaced jaws arranged on either 55 side of said body on the bottom and rear wall thereof, said jaws being adapted to successively rock upon the transverse supports, one of said jaws being located at the rear of the body bottom, another at the corner 60 of the body bottom and the rear wall of the body and the third on the rear wall of the body, and means adjacent the front of the bottom of the body for sup- 65 porting the body in horizontal position when it is resting on the forwardmost transverse support and forwardmost jaws, the rear-

most of said transverse supports being lower than the forward supports, and a depending bracket on either side of the body extending between two of said transverse supports and under one of them, and limiting 70 means having associated therewith resilient means to limit the rearward movement of said body to prevent it leaving the supports entirely, and means for supporting said limiting means and resilient means in a pre- 75 determined position.

4. In an automatic dump body construction, a supporting frame having spaced side members and transverse supports joining said spaced side members, a dump body 80 having an overhanging rear portion and so arranged that when empty it will maintain the position to be loaded and loaded will tend to attain a position to be unloaded, a plurality of spaced jaws arranged on either 85 side of said body on the bottom and rear wall thereof, said jaws being adapted to successively rock upon the transverse supports, one of said jaws being located at the rear of the body bottom, another at the corner 90 of the body bottom and the rear wall of the body and the third on the rear wall of the body, and means adjacent the front of the bottom of the body for supporting the body in horizontal position when it is 95 resting on the forwardmost transverse support and forwardmost jaw, the rearmost of said transverse supports being lower than the forward supports, and a depending bracket on either side of the body extending 100 between two of said transverse supports and under one of them, a latch member adapted to engage with said body to hold it in horizontal position, yielding means to maintain said latch member in position, and means associated with the vehicle for unlatching said latch from the body to permit it to dump when loaded by rocking on the successive supports.

5. In combination, side rails, transverse 110 rods located at spaced intervals therein, broad bearing members supporting said rods in said side rails, a dump body, a plurality of spaced rocking jaws on either side of the bottom and rear wall of the body, said 115 jaws having broad bearing faces adapted to rest on said transverse rods adjacent the said rails on either side of the body, means to position the body when in horizontal position and supported at its forward end 120 on the side rails.

6. In combination, side rails, transverse rods located at spaced intervals therein, broad bearing members supporting said rods in said side rails, a dump body, a plurality of spaced rocking jaws on either side of the bottom and rear wall of the body, said 125 jaws having broad bearing faces adapted to rest on said transverse rods adjacent the said rails on either side of the 130

body, means to position the body when in horizontal position and supported at its forward end on the side rails, means to detachably, automatically latch said body 5 when it assumes a horizontal position, means to unlatch it at will, and means to yieldingly limit the movement of the body when

it dumps upon being unlatched and when unloading.

In testimony whereof, we affix our signatures.

RALPH E. SMITH.
JOHN C. GAY.
ROY J. ARNOLD.
